UNITED STATES PATENT OFFICE

GEORGE D. DOHERTY, OF EVANSTON, ILLINOIS, ASSIGNOR TO DOHERTY-BREHM COMPANY, OF CHICAGO, ILLINOIS, A CORPORATION OF DELAWARE

HUMIDIFYING APPARATUS

Application filed November 11, 1931. Serial No. 574,312.

This invention relates to an apparatus for heating and humidifying the atmosphere of rooms or other enclosures, and has special reference to improvements upon the means 5 shown and described in my Patent No. 1,760,976 dated June 3, 1930.

More particularly this invention has reference to an apparatus comprising sections for circulating a heating medium which sections are constructed and arranged to accommodate a humidifying medium in close thermal relation with a heating medium to maintain a desired degree of relative humidity and temperature.

15 An object of this invention is to provide a device of the character indicated for heating and humidifying the atmosphere wherein the humidifying medium is in direct contact with the surface of the sections in which 20 the heating medium is circulated.

Another object of this invention is to provide a device of the character indicated wherein the humidifying medium may flow from an upper section to a lower section with 25 substantially no direct drop from one section to another, thereby obviating any noise or spattering which might be caused by the direct drop of the humidifying medium from one section to another. This is accomplished 30 by providing each section with an inclined portion extending below the section down which the humidifying medium flows to the section thereunder.

A further object of this invention is to 35 provide a heating and humidifying section whereby the flow of the humidifying medium will be toward the downwardly extending, inclined discharge portion thereof.

Still another object is to provide a heating and humidifying apparatus wherein there is a constant circulation of air about 40 said sections and the humidifying medium therein.

A still further object is to provide an apparatus wherein a portion thereof may be used 45 to heat and humidify the air circulating therethrough, or, if desired, it may be used merely to superheat the air which has already been heated and humidified by the 50 lower sections.

Further objects and advantages will be apparent from the following description when taken together with the accompanying drawings in which latter:

Figure 1 is a front elevational view of 55 the apparatus with the front of the casing broken away and showing one of the heating and humidifying sections partially in section;

Fig. 2 is a side elevational view of Fig. 60 1 showing the casing therefor in section;

Fig. 3 is a view taken on the line of 3—3 of Fig. 1;

Fig. 4 is a perspective view of one of the 65 heating sections embodied in the apparatus;

Fig. 5 is a perspective view of another form of section;

Fig. 6 is a perspective view showing two 70 sections of still another form arranged in staggered relation;

Fig. 7 is a perspective view of a section 75 similar to those shown in Fig. 6 but being provided with two air passageways instead of one;

Fig. 8 is a vertical cross-sectional view of a 80 portion of the apparatus formed of similar sections connected together; and

Fig. 9 is a vertical cross-sectional view of 85 a portion of another form of apparatus in which different sections are alternately arranged to provide a tortuous path for the air.

Referring more particularly to the drawings, a preferred embodiment of the present invention is shown particularly in Figs. 1, 2 and 3. The construction shown therein 90 comprises a group of superposed horizontally extending heating sections 1 and 2. Each of the sections 1 and 2 is provided with similarly positioned annular shoulders 3 having the inner faces thereof threaded. Nipples 4 are threaded into the shoulders 3 to connect the ends of the castings 1 and 2 together in a unified structure to form a continuous passageway therethrough for a heating medium.

Plugs 5 are threaded into the upper shoulders on the upper section 1 to prevent the escape of the heating medium therethrough. The lower end of one of the headers, thus formed, is connected to an inlet 6 and the 100

lower end of the other is connected to an outlet 7. With this construction, the heating medium enters through the inlet 6 and circulates through the various sections and then 5 escapes through the outlet 7.

The lowermost heating section 1a is provided with legs 8 or other suitable supporting means upon which the weight of the entire structure rests. This section is likewise 10 made substantially larger than the other sections so that if there is any overflow of the heating medium from the sections above, the same will be caught in the lowermost section from which it may escape through the 15 drain 9.

One form of section embodied in the present invention is shown in Figs. 1, 2 and 3. These sections comprise a casting having longitudinally extending passageways 10 extending therethrough in communication with the headers formed by means of the nipples 4 inter-connecting adjacent heating sections. 20

An air passageway 11 is formed centrally of the sides of the section and an upwardly 25 extending flange 12 is provided about the upper edges of the section to form a recessed portion for containing a humidifying medium on the upper face of the casting. A flange 13 is also provided around the passageway 11 to prevent the escape of any of the humidifying medium through the passageway.

Each of the castings, except the lowermost one, is provided with a preferably trough-like spillway 15 at one side, preferably an end, which extends a distance below the rest of the casting. The sides of the spillway are preferably tapered so as to converge towards the center thereof as shown particularly in 15 Figs. 1 and 2. When the sections are connected together, the lower end of the spillway 15 extends downwardly to a point slightly above the upper surface of the casting next below, so that the overflow of the humidifying liquid from a casting will flow down 45 the sides of the spillway into the recessed portion of the casting thereunder with substantially no direct drop of the humidifying medium.

50 While I have shown and described a particular form of spillway, it is to be understood that other forms may be used without departing from the scope of this invention.

The flange 12 also extends about the edges 55 of the upper end of the spillway 15, the height of the flange being lowest there, so that any excess of the humidifying medium will flow over the flange at this point and down through the spillway 15. As shown 60 in Figs. 1 and 3, the flange 12 may be of uniform height throughout except for the portion about the upper edges of the spillway 15. Here the flange may taper downwardly toward the inner end of the spillway where 65 it is preferably about $\frac{1}{8}$ " in height. If de-

sired, the whole flange may gradually taper from the side opposite the spillway down to the portion adjacent the upper edge of the spillway, which, as stated, is only about $\frac{1}{8}$ " in height at the inner end of the spillway. 7

This form of flange is shown in Fig. 5.

The casings are arranged with the spillways at opposite ends of alternate sections so that the humidifying medium enters the recess in the upper portion of the casting at one end, flows to the other end, out of the spillway 15 and into the end of the casting thereunder, at which point the flange 12 is highest, thus reversing the direction of flow through the alternate castings and being discharged from the end where the flange 12 is of least height. With this construction, although the castings are preferably arranged in a horizontal position, a deviation therefrom will not affect the circulation of the humidifying medium 8 through the castings nor cause it to escape therefrom except through the inclined discharge 15.

The form of casting shown in Fig. 4 differs only slightly from that shown in Figs. 9 1, 2 and 3. In Fig. 4, the flange 12a tapers from the side opposite the spillway to the portion adjacent the outer edges of the spillway, the same as that shown in Fig. 5. From here it slopes down so that at the inner edge 6 of the spillway it is flush with the top surface of the casting. When this form of casting is employed, only a thin sheet of water passes over the surface, providing for more rapid evaporation of the humidifying 100 medium.

The humidifying medium preferably employed is water which is supplied through the conduit 16 to the standpipe 17 through the pipe L 18. Nozzles 19 are connected to the standpipe 17 so as to supply the water or other humidifying medium to different castings as desired. The flow of the humidifying medium to the standpipe 17 is controlled by a valve 20, and the pressure in the standpipe 17 is controlled by a pressure valve 21 so that the pressure may be adjusted and will remain constant thereafter until again altered by adjustment of the valve 21. 110

The castings 1 differ from the castings 2 115 in that the former are provided with a cut-out portion 22, the sides of which engage the standpipe 17. Pins 23 are inserted across the cut-out portion adjacent the standpipe to hold the same immovable with respect to the castings. The standpipe 17 is vertically supported by the special L 18 which rests on the lowermost casting. Such a construction provides for great rigidity and prevents any rattling or knocking of the standpipe in the 120 castings which would otherwise be present whenever there was any vibration.

The present apparatus is designed for use with steam, vapor or hot water heating systems. When used with a hot water heating 125

- system, it has been found desirable to use all the castings both for heating and humidifying, while when used with steam or vapor heating systems, it is unnecessary to use the 5 upper sections for humidifying, the lower sections being sufficient for this purpose, and when so used the upper sections merely superheat the air which has been already saturated and heated to a certain extent.
- 10 By the use of the nozzles 19 connected to the standpipe 17 at various heights, the same apparatus may be efficiently used with a hot water system by supplying the humidifying medium to the upper section and letting it 15 drain down, or to both the upper section and an intermediate section, or the apparatus may be converted for use with steam or vapor by supplying the humidifying medium only to an intermediate section so that the upper sections act merely to superheat and not to 20 humidify.

Furthermore, the evaporation may be more completely controlled by the use of the nozzles 19 at different heights, a greater evaporation taking place when all the humidifying medium is supplied to the castings through the upper nozzle and less taking place when no humidifying medium is supplied to the upper sections.

25 Referring to Fig. 6, a modified form of casting or heating section 24 is shown which is preferably rectangular in shape. At one end thereof, there is an inclined trough-like spillway 25 having sides 26 to direct the 30 flow of the humidifying medium therein. The spillway 25 extends outwardly from the end of the casting 24. An upwardly extending flange 27 is positioned about the edges of the upper surface of the casting to form a 35 recess for containing the humidifying medium.

The flange 27 is preferably formed with a reduced portion 28, in front of the spillway 25, forming a lip which serves to maintain a 40 supply of the humidifying medium in the casting and at the same time insures that any excess thereof will flow over the lip 28 and down the spillway 25. Although the flange 27 may be of uniform height, except for the 45 lip portion 28, it may also be formed to taper from the end opposite the spillway gradually down to the spillway. If desired, a form of flange similar to the flange 12a, shown in Fig. 4, may also be employed with a casting 50 of this type by omitting the lip 28 in front of the spillway.

When this form of casting is employed, due to the fact that the spillway 25 extends outwardly from the end of the casting, it is 55 necessary to longitudinally stagger the castings as shown in Fig. 6 so that the receiving end of the casting extends outwardly of the spillway 25 of the casting above. In order to connect the castings 24 together by means of the nipples 4, the annular supporting

shoulders 29 are positioned so that those adjacent the spillway are closer to the end than the others so that when they are arranged in staggered relation they will be vertically aligned.

As in the casting previously described, the casting 24 is provided with an air passageway 30 having a flange 31 around the edges thereof to prevent any of the humidifying liquid from escaping therethrough.

Referring to Fig. 8, similar castings having a single air passageway may be connected together so that the air passageways are vertically aligned. It is to be noted that the lower surfaces of the castings taper upwardly from the sides to the lower end of the air passageway, thus as the air passes up through the air passageway of one casting, it will rise up through the air passage of the casting above at the same time drawing in additional air over the humidifying medium, thereby forming a circulation of air through the apparatus and preventing the formation of air pockets over the humidifying medium.

In Fig. 5 the casting is provided with two air passageways 11a instead of the single air passageway 11. If desired, instead of forming the structure of similar castings as shown in Fig. 8, castings having an unequal number of air passageways may be employed in alternate relation as shown in Fig. 9. This construction provides for an even better circulation of air through the apparatus, due to the tortuous path which it must take because of the staggered relation of the air passageways.

The casting shown in Fig. 7, differs from those shown in Fig. 6 only in that two air passageways 30a are employed instead of the single air passageway 30. These two forms may also be employed alternately to form the apparatus with the same result as when the form shown in Figs. 3, 4 and 5 are combined.

In the operation of the apparatus, the humidifying medium enters a casting 1 from one of the nozzles 19, and when the level of the humidifying medium reaches the upper edge of the flange adjacent the spillway, it flows down and into the recessed portion of the casting below and so on down through all the castings to the bottom one from which any excess is drawn off through the outlet 7.

By means of the pressure valve 21, the flow of the water through the upper casting 19 may be controlled so that once the recessed portions of the castings are full, very little of the humidifying medium in excess of that dissipated through evaporation will flow into the section fed by the nozzle 19. The whole apparatus is automatic and after once being set requires no further adjustment, for it is well known that in cold weather the air is very dry and contains considerably less moisture than in warm weather. As the radiator

is naturally used more for heating purposes in cold weather than in warm weather, a greater amount of evaporation takes place, keeping the humidity of the atmosphere relatively constant at all times.

While I have shown and described various preferred embodiments of this structure, it will be apparent to those skilled in the art that various modifications thereof may be made without departing from the spirit and scope of this invention and therefore I wish to be limited only by the prior art and the scope of the appended claims.

I claim:

5. 1. In a device of the character described, a hollow casting for circulating a heating medium and having an exposed recessed portion for containing a humidifying medium, one side of said casting having a cut-out portion to form an inclined spillway extending downwardly below the casting down which the excess of the humidifying medium flows to a casting therebelow.
10. 2. In a device of the character described, a hollow casting for circulating a heating medium and having an exposed recessed portion for containing a humidifying medium, one side of said casting having a cut-out portion to form an inclined spillway with the sides thereof extending below the bottom of said casting and converging centrally of the cut-out portion.
15. 3. In a device of the character described, a hollow casting for circulating a heating medium and having a flange around the upper surface thereof forming a recessed portion for containing a humidifying medium, and an inclined spillway extending downwardly below said casting, said flange having a reduced portion adjacent said spillway to permit any excess of the humidifying medium to flow down over the spillway to the casting below.
20. 4. In a device of the character described, a hollow casting for circulating a heating medium and having a flange around the upper surface thereof forming a recessed portion for containing a humidifying medium, and an inclined spillway at one side extending downwardly below said casting, said flange tapering down to the surface of said casting adjacent said spillway to permit any excess of the humidifying medium to flow down over the spillway to the casting next below.
25. 5. In a device of the character described, a hollow casting for circulating a heating medium and having a flange around the upper surface thereof forming a recessed portion for containing a humidifying medium, and an inclined spillway extending downwardly below said casting, said flange being of greatest height at the side of the casting opposite the spillway and tapering down to

and being of less height at the portion adjacent said spillway to permit any excess of the humidifying medium to flow down over the discharge to the casting below.

6. In a device of the character described, a hollow casting for circulating a heating medium and having an exposed recessed portion for containing a humidifying medium, and an inclined toboggan-shaped spillway extending outwardly from one side of said casting and downwardly below the bottom thereof to permit any excess of the humidifying medium to flow down over said spillway to a casting below. 70

7. In a device of the character described, comprising a plurality of spaced and superposed heating sections connected to one another for circulating a heating medium therethrough, said heating sections having exposed recessed portions for containing a humidifying medium, and inclined spillways extending downwardly from said sections and lying within the vertical planes bounding the sides of said sections over which the excess of humidifying medium of one section flows to the section next below. 80

8. In a device of the character described, comprising a plurality of spaced and superposed castings connected together for circulating a heating medium therethrough, said castings having exposed recessed portions for containing a humidifying medium, and an inclined spillway extending outwardly and downwardly from the opposite ends of alternate castings, said castings being arranged in staggered relation with the spillway ends of the castings disposed inwardly of the corresponding ends of the castings next below, whereby the humidifying medium flows downwardly over the spillways into the outwardly extending ends of the castings next below. 90

9. In a device of the character described, comprising a plurality of spaced and superposed hollow castings connected together for circulating a heating medium therethrough and having recessed portions for containing a humidifying medium, spillways for discharging the excess of humidifying medium in a casting to the casting next below, a supply line for supplying a humidifying medium to certain of said castings and means for controlling the flow through the supply line to said individual castings whereby all of said sections may be used for heating and humidifying the atmosphere, or the upper sections may be merely used to superheat the atmosphere already heated and humidified by the sections below. 100

10. In a device of the character described, a hollow casting for circulating a heating medium and having an exposed recessed portion for containing a humidifying medium, and an inclined spillway extending down- 110
115
120
125
130

wardly below said casting, the side of said recessed portion being reduced adjacent said spillway to permit any excess of humidifying medium to flow over said reduced portion 5 and down said spillway to a casting below.

11. In a device of the character described, a hollow casting for circulating a heating medium and having an exposed recessed portion for containing a humidifying medium, 10 and an inclined spillway extending downwardly below said casting, the side of said recessed portion tapering down to the bottom of said recessed portion adjacent said spillway to permit any excess of humidifying 15 medium to flow down over said spillway to a casting below.

12. A device of the class described comprising a plurality of spaced and superposed heating sections connected to one another for 20 circulating a heating medium therethrough, certain of said sections having a single air passageway extending therethrough and others of said sections having a plurality of air passageways extending therethrough, 25 sections having a single air passageway being alternately disposed with sections having a plurality of air passageways, and means on each heating section containing a humidifying medium for imparting the humidity to 30 the heated air.

13. A device of the class described comprising a plurality of spaced and superposed heating sections connected to one another for 35

circulating a heating medium therethrough, certain of said sections having a single centrally located air passageway extending therethrough and others of said sections having a plurality of air passageways spaced 70 about the central portion of said sections and extending therethrough, sections having a single air passageway being alternately disposed with sections having a plurality of air passageways whereby the passageways are 75 staggered to form a tortuous path for the air, and means on each heating section containing a humidifying medium for imparting the humidity to the heated air.

14. In a device of the character described, comprising a plurality of spaced and superposed hollow castings connected together for circulating a heating medium therethrough and having recessed portions on their upper 80 faces for containing a humidifying medium such as water, spillways for discharging the excess of humidifying medium contained in the recessed portion of a casting to the recessed portion of the casting next below, a supply line for delivering the humidifying 85 medium to recessed portions of certain of said castings, and means for controlling independently the delivery of the humidifying medium to some of said recessed portions of the individual castings. 90

In witness whereof, I have hereunto subscribed my name.

GEORGE D. DOHERTY.
